MACHINE FOR SHAPING UPPERS OVER LASTS

Original Filed March 16, 1923 3 Sheets-Sheet 3

UNITED STATES PATENT OFFICE.

ARTHUR F. PYM, OF MARBLEHEAD, MASSACHUSETTS, ASSIGNOR TO UNITED SHOE MACHINERY CORPORATION, OF PATERSON, NEW JERSEY, A CORPORATION OF NEW JERSEY.

MACHINE FOR SHAPING UPPERS OVER LASTS.

Application filed March 16, 1923, Serial No. 625,592. Renewed February 2, 1927.

This invention relates to machines for use in the manufacture of boots and shoes for shaping the upper materials, and is herein illustrated in its application to a well-known 5 type of bed lasting machine and more particularly as applied to means for shaping the toe portion of the upper materials. It will be recognized, however, that in many of its aspects the invention is not limited to a 10 machine of the type shown nor restricted to the shaping of the toe end of the upper.

In one important aspect the invention relates to the positioning of lasting mechanism in relation to the shoe, and a feature of the 15 invention consists of a novel organization of power-operated mechanism for effecting relative movement of lasting mechanism and a shoe with means for controlling said power mechanism as determined by each 20 particular shoe. The machine herein shown comprises power-operated means for effecting in a predetermined manner relative movement of a shoe support and lasting mechanism heightwise of the shoe to accomplish what is usually termed the upwiping of the upper and relative movement thereafter to wipe the upper inwardly over the 25 bottom of the shoe, and includes in its organization a device controlled by engagement with the bottom of the shoe for setting the power driven parts in such a manner as to insure the termination of the upwiping operation with the lasting mechanism 30 in proper position for the overwiping operation without loss of control of the upper.

In accordance with a further feature, the 35 invention provides means for insuring that the lasting mechanism will operate uniformly on different shoes, the construction shown comprising means for bringing the wipers into engagement with the shoe at the same predetermined distance from the plane 40 of the shoe bottom in operating on different shoes. While this feature of the invention is not limited to a power-operated organization, it has important advantages in a machine where the wipers are closed automatically about the toe at a predetermined time 45 in the cycle to effect the upwiping operation, since it insures that the wipers will not engage the shoe so far from the plane of the 50 shoe bottom as to interfere with their

proper conforming action in the relative upwiping movement of the shoe and the wipers. In the illustrated embodiment of the invention regulation of the extent of the upwiping, together with the proper positioning of the wipers at the end of the upwiping as hereinbefore explained, are effected by co-operating mechanisms one of which imparts to the wipers an invariable movement heightwise of the shoe in operating on different shoes while the other is adjustably variable as determined by the particular 60 shoe to determine the distance from the plane of the shoe bottom at which the upwiping operation begins and consequently the position of the wipers relatively to the plane of the shoe bottom at the end of the 65 upwiping operation.

A further feature of the invention consists in a novel organization in which lasting or wiping mechanism which is yieldable in response to resistance of the shoe before it is 70 moved inwardly over the bottom of the shoe is differently controlled in such inward movement, the construction shown comprising spring means permitting the wipers to yield in conformity to the shoe in the upwiping operation together with locking means which acts both to prevent further yield and also to prevent reaction of the 75 spring means in the overwiping operation. This feature is herein illustrated in its application to wiper operating means including separate springs for controlling the advance and the closing of the wipers, with locking devices associated with the different 80 springs to afford positive control as the 85 wipers are advanced and closed over the bottom of the shoe. By thus preventing reaction of the spring means which controls engagement with the shoe in the upwiping 90 operation insurance is afforded that the wipers will not be suddenly projected over the bottom of the shoe or moved inwardly 95 farther than would be desirable, for example in lasting a shoe of the welt type, and by eliminating further yield of the spring 100 means in the overwiping operation better control of the wipers is afforded to insure that they will be moved inwardly the precise distance desired. While the construction shown thus combines both these advantages, 105 it will be recognized that the invention is

not limited to an organization in which the yielding means is controlled in the particular manner illustrated.

Another feature of the invention consists in an organization having means for adjusting relatively the extent of the advancing movement and the extent of the closing movement of the wipers, for example to provide for different extents of closing movement for a given extent of advancing movement when operating on shoes of different styles and sizes. In the construction shown the desired result is accomplished by the provision of means for varying relatively the rates of the advancing and closing movements of the wipers. It is well understood that the amount of angular closing movement of end embracing wipers required to force them inwardly a given distance from the edge of the shoe bottom at the sides of the shoe, for the same amount of advancing movement lengthwise of the shoe, depends upon how nearly the sides of the shoe approach a parallel relation to the longitudinal median line of the shoe, a greater proportional amount of such closing movement being required on narrow pointed toes than on comparatively round toes. In the use of prior constructions having means for imparting to wipers predetermined advancing and closing movements it has been possible only to effect a rough approximation to conditions which are desirable for the best results, and for wide variations of styles or shapes it has been necessary to substitute different parts in order to insure that the wipers will operate effectively at the sides of the toe as well as at the end of the toe. By the use of the present invention the best conditions in respect to advancing and closing movements of the wipers may be readily secured without substitution of parts and without any substantial loss of time. The construction shown affords provision for varying both the extent of the advancing movement and the extent of the closing movement of the wipers, which is a further advantage in that it permits the machine to be readily adapted, for example, to operate on welt shoes or McKay shoes.

A further feature of the invention consists in novel means of control to enable the operator to produce different results in the operation of the machine, the construction shown comprising means to determine different stopping positions of the operating mechanism, together with a manually operated controlling member which is movable to different positions to determine in which of the stopping positions the machine will come to rest and also to determine how long the machine will operate before it comes to a stop. More particularly, the construction illustrated provides for stopping the machine with the wipers located either in the

position which they occupy at the end of the upwiping movement or in the position which they occupy when the upper is to be fastened, for example by wiring or tacking, and further provides for such control that the machine may be made to operate through its entire cycle any selected number of times.

Still another feature consists in a novel construction and arrangement of means for imparting operative movements to the lasting mechanism or wipers. In its embodiment of this feature the machine shown is provided with separate and operatively independent trains of mechanism for imparting respectively to the wipers their advancing and closing movements, such mechanism including power transmitting elements so constructed as to maintain a continuous operative relation to the wipers in different positions of the wipers which they assume, for example, as a result of their operative movement heightwise of the shoe or of adjustments to position them correctly in relation to the shoe. By reason of the relation between the different trains of mechanism, the extent of movement required of either of them to effect the proper operation of the wipers is not affected in any degree by the extent of movement of the other. This greatly facilitates the design of the operating parts or cams, permits the position of the wipers lengthwise of the shoe and their relation to each other to be readily varied independently by adjustment of the respective trains of operating mechanism, and prevents the relation of the wipers to each other from being disturbed by any bodily yield of the wipers lengthwise of the shoe that may occur in the upwiping operation.

The above and other features of the invention, including various details of construction and novel combinations of parts, will now be more particularly described by reference to the accompanying drawings and pointed out in the claims.

In the drawings,

Fig. 1 is an end elevation of a lasting machine embodying my invention;

Fig. 2 is a rear elevation of part of the stopping and starting mechanism;

Fig. 3 is a front elevation, partly broken away, of as much of the lasting machine shown in Fig. 1 as is necessary to illustrate my invention.

Fig. 4 is an end elevation on an enlarged scale showing part of the mechanism of Fig. 1 including the drive shaft and the cams and levers operated thereby;

Fig. 5 is partly a top plan view and partly a section on the line 5-5 of Fig. 3, showing part of the wiper operating mechanism;

Fig. 6 is partly a top plan view and partly a horizontal section showing the wipers and wiper carriers and operating connections therefor; and

Fig. 7 is a side elevation showing a modification of part of the connections of Fig. 3.

The machine comprises generally a suitable frame 20 upon which is mounted a shoe

- 8 supporting jack 22 and a toe rest 24 for an assembled last and shoe in the position shown in dotted lines in Fig. 3. The heel seat of a shoe supported by the jack 22 is arranged to be lasted by suitable mechanism
- 10 indicated generally at 26. Power may be supplied to the machine by means of a belt driving a pulley 28 (Fig. 1) which is arranged to run continuously and which is connected to the jacking mechanism by a suitable one-revolution clutch controlled by a knee lever (not shown). These parts may be, and are illustrated as being, the same as parts more fully illustrated and described in Patents Nos. 1,018,477, granted Feb. 27,
- 15 1912; 1,390,755, granted Sept. 13, 1921; and 1,373,482, granted April 5, 1921, all on applications of Matthias Brock. The jacking mechanism is released, after a shoe has been lasted, in response to a second operation of 20 the knee lever, as fully described in said patents.

Wipers 30 are arranged to be operated by power-driven connections, hereinafter described, for upwiping and overwiping the toes of shoes held by the above-described jacking mechanism. These wipers are secured in carriers 32 (Fig. 6) arranged to be moved angularly in a head or carrier 34, to close them about the end of a shoe, by pinions 36 meshing with rack teeth formed on the edges of the carriers. The pinions 36 are operated by a pair of racks 38 engaging an equalizing pinion 40 mounted on a sliding rod or plunger 42.

- 40 The head 34 carrying the wipers and wiper carriers is integral with or secured to an inner sleeve or plunger 44 surrounding the plunger 42, the sleeve 44 being longitudinally movable, to advance and retract the wipers, in an outer sleeve 46 which is formed as part of a head 48 pivotally mounted on a shaft 50 (Fig. 3). The head 48 may be tilted about shaft 50 in alining the wipers with the bottom of a shoe by manipulating a handle 52
- 45 as described in the above-identified Brock patents.

Shaft 50 is carried by a slide 54, which may be angularly adjusted on a slide 58 about a vertical axis passing adjacent the toe rest by manipulating a hand wheel 56, in such a manner as to turn the wipers in a horizontal plane to aline them with the median line of the forepart of the shoe. Slide 58, in turn, is mounted on a second slide 60 by a dovetail connection, for horizontal movement laterally of the machine, and is arranged to be automatically operated during the operation of upwiping the shoe as described in said Patent No. 1,390,755. Slide 60 and the parts carried thereby are ar-

ranged for adjustment longitudinally of the machine on a head 62 carried by a vertical slide 64, a hand wheel 66 being provided for facilitating such adjustment.

The wipers 30 may be tilted about an axis 70 extending longitudinally of the machine, to aline them transversely with the shoe bottom, by manipulating a handle 68 to turn a threaded bolt 70 carrying a traveling nut 72 connected by a link 74 with a shaft 76 seated in a recess in the head 34.

The shoe is held clamped against toe rest 24 by a holddown 80 mounted on an arm 82 which in turn is carried by a sleeve 84. Sleeve 84 is arranged to swing about a reduced central portion of an inner sleeve 86 threaded on a vertically sliding rod 88 and arranged to be turned by a suitable handle 90 to adjust the position of the holddown by raising or lowering it relatively to rod 88. Sleeve 86 is held in adjusted position by engagement of a spring pawl 92 (Fig. 3) carried thereby with a ratchet 94 mounted on rod 88. Rod 88 is operated to lower the holddown against the shoe by a link 96 operated by a treadle 98, which is held down by a pawl and ratchet and which is released after the shoe has been lasted by a push rod 100 connected to the pawl and ratchet and to the jacking mechanism, and also to a special pawl-releasing device, as described in the said Brock patents.

A bracket 110 is clamped on the lower end of rod 88 in predetermined relation to the position of holddown 80 and is formed with a vertical recess which is T-shaped in cross-section and in which a rack block 112 is mounted for vertical adjustment. As will be explained, rack block 112 operates to vary the position of power driven connections for raising and lowering slide 64 according to the vertical position of holddown 80 when clamped against a shoe, so that vertical movement of slide 64 in upwiping the shoe is limited in such a manner as to position the wipers 30 in predetermined relation to the plane of the shoe bottom. Rack block 112 is arranged to be adjusted vertically by a bolt 114 threaded through a vertical recess in said block and journaled at its lower end in bracket 110 to prevent it from moving vertically relatively to the bracket. Bolt 114 is connected by a universal joint 116 to a telescopic shaft 118 which is connected to the vertical adjusting device operated by handle 52 for tilting wipers 30 about shaft 50. By this arrangement adjustment of the wipers by manipulation of handle 52 operates through telescopic shaft 118 to raise or lower rack block 112 in its bracket 110 in such a manner as to compensate for changes in the vertical position of the wipers due to such adjustment.

Rack block 112 meshes with a sector 120 mounted on a rock shaft 122 which carries

an arm 124 connected by a link 126 to an arm 128. This arm carries at one end a pinion 130 meshing with a rack 132 formed on, or secured to, the lower end of the vertically moving slide 64. The pinion also meshes with a second rack 134 which is stationary during the early portion of the operation of the machine. The lower end of arm 128 carries a sliding block or roll arranged for movement in a curved slot 136 of a cam operated lever 138, in such a manner that movement of rack block 112 in clamping the holdown against a shoe operates through arms 124 and 128 to change the effective length of the lever without moving the pinion 130. Lever 138 is arranged to rock about a shaft 140 mounted in arms 142 and 144 (Figs. 3 and 4) carried by the machine frame. When the lever is rocked about shaft 140 by its cam, herein-after described, it operates through arm 128 to move pinion 130 upwardly. The pinion rolls on rack 134, which is at this time stationary, and therefore operates through rack 132 to move slide 64 and the parts carried thereby upwardly a variable distance according to the effective length of lever 138 to position wipers 30 the same predetermined distance below the plane of the bottom of each shoe before the wipers are closed about the toe for the upwiping operation. Insurance is thus afforded that, whatever may be the vertical position of the toe, the wipers will not engage the shoe too far from the plane of the sole for the best results in the upwiping of the upper materials.

Lever 138 is operated and continuously controlled by a face or path cam on one side of a cam member 146 (Figs. 3 and 4) mounted on a cam shaft 148 journaled in arms 142 and 144 of the machine frame. Cam shaft 148 is arranged to be driven, under the control of the operator, from pulley 28 by worm 150 (Figs. 1 and 4) meshing with a worm wheel 152. The worm wheel is connected by spring pins 154 with one member of a Horton clutch 156, of well-known construction, so that in case the machine jams the spring pins 154 will slip and the driving mechanism will not be injured. Worm wheel 152 is loosely mounted on shaft 148 and only drives the shaft when it is connected thereto by manipulation of the Horton clutch 156. This clutch is formed with two disks 158 (Figs. 2 and 4) secured together, one of which is formed with a stop "a" or abutment to be engaged by a controller 160 and the other of which is formed with two similar stops "b" and "c" or abutments to be engaged by a controller 162. Controllers 160 and 162 are of the type which is ordinarily used for controlling a Horton clutch, and are mounted on the ends of the longer arms of a 3-arm

lever 164. This lever is carried by a bracket extending from the machine frame and is operated by a link 166 connected to a bell crank lever 168 loosely mounted on shaft 122, the bell crank lever being in turn connected by a link 170 with a treadle 172 (Figs. 1 and 3).

This arrangement is such that when the treadle 172 is in its upper position (in which it is held by a suitable spring) the 3-arm lever 164 is rocked so that the controller 162 will engage its disk 158 to disconnect the Horton clutch with the parts either in starting position or in a different position, as hereinafter more fully explained, depending upon which of the two abutments "b" and "c" on the disk is engaged by the controller. On the other hand when treadle 172 is completely depressed, the 3-arm lever 164 is rocked in the opposite direction so that controller 160 engages the abutment "a" on its disk 158 to disconnect the clutch from cam shaft 148 with the parts of the machine in still another position. When treadle 172 is held in an intermediate position, neither of the controllers 160, 162 engages its disk 158, so that the mechanism operated by cam shaft 148 repeats its cycle of operations over and over again until the operator either releases the treadle or completely depresses it. Suitable foot-controlled catches may, if desired, be provided for holding the treadle in its intermediate or in its depressed position.

The above described rack 134, meshing with pinion 130, is mounted on a vertical slide and is connected to a bell crank lever 180 through a link and a heavy coil spring 182 (Fig. 3) in such a manner that downward movement of the rack is effected positively through the link while upward movement is effected yieldingly through the spring 182. As shown in Fig. 4, lever 180 carries a cam roll running in a cam track formed in one face of a cam 184 mounted on cam shaft 148. Thus cam 184 imparts a predetermined downward movement to rack 134 through lever 180 to move slide 64 and the parts carried thereby upwardly a predetermined distance, after the wipers 30 have preliminarily been positioned by lever 138. Lever 138 is at this time held stationary by a dwell in its cam so that movement of rack 134 turns pinion 130 to operate rack 132 to impart the desired vertical movement to slide 64. By this operation of rack 134 the upwiping operation is effected and during the overwiping operation (hereinafter described) the rack is yieldingly moved in the opposite direction through spring 182 to force the wipers first lightly and then heavily against the wiped-over upper materials to iron them down against the shoe bottom.

The wipers 30 are advanced and closed by

independently operable connections driven from cam tracks in the faces of cams 146 and 184 which operate on cam rolls carried by bell crank levers 190 and 192, loosely mounted on a shaft 194 carried by arms 142 and 144 of the machine frame. Levers 190 and 192 are connected to a pair of plungers 196 (Figs. 3 and 5) each of which is surrounded by a sleeve 198 which is operated by its plunger 196 through a coil spring 200 confined between a shoulder on plunger 196 and a bushing 202 threaded in the end of sleeve 198. Each bushing 202 is formed with a knurled head 204 by means of which it may be adjusted to vary the compression of spring 200, and a lock nut 206 is provided for securing each bushing in adjusted position. Each plunger 196 carries lock nuts 208 (Fig. 5) arranged to engage the head 204 of the corresponding bushing to move sleeve 198 positively toward the left in Fig. 5 to a predetermined initial position to adjust the wipers, as more fully hereinafter explained.

Sleeves 198 are formed with rack teeth to engage and drive pinions 210 and 212 carried by vertical shafts journaled in arms 144 and 142 of the machine frame. These arms are extended downwardly to form a stationary casing 214 in which sleeves 198 may slide, and in which housings for pinions 210 and 212 are formed. Pinion 210 is connected through its vertical shaft by a universal joint to a vertical telescopic rock shaft 216 and similarly pinion 212 is arranged to drive a telescopic rock shaft 218.

At its upper end rock shaft 218 is connected by a universal joint to a rock shaft 219 journaled in a pair of arms 220 integral with or secured to the head 48 supporting wipers 30 and their operating mechanism. The rock shaft 218 is formed in two relatively rotatable parts (Figs. 3 and 6) the lower part carrying an arm 222 which seats against an arm 224 carried by the upper part; and the rock shaft 219 has fast thereon a toothed segment 226. When arm 222 is rocked to the right in Fig. 6 it operates segment 226 by direct engagement with arm 224. When it is rocked to the left in that figure it operates the segment through a coil spring 228 engaging an adjustable head 230 on a bolt 232 which passes loosely through openings in arms 222 and 224 and is formed with a fixed head to engage arm 224.

Segment 226 is in driving engagement with a rack 234 carried by an arm extending from a sleeve 236 surrounding a reduced portion formed on the sleeve 44 which carries head 34. Thus head 34 is moved back and forth to advance and retract wipers 30 by rock shaft 218 operating through rack and segment 226 and 234. Sleeve 44 is free to turn in sleeve 236 and the latter is main-

tained in a horizontal position regardless of the angular adjustment of sleeve 44 by means of upper and lower guide flanges 238 slidingly engaging rack 234.

Rock shaft 216 is connected by a universal joint to a rock shaft 239 journaled at its upper end in a pair of arms 240 formed as an extension of sleeve 236 so as to move back and forth with sleeve 44 while being maintained in a horizontal position by guide flanges 238. Similarly to the rock shaft 218, the shaft 216 comprises two relatively rotatable parts, of which the lower part carries an arm 242 engaging an arm 244 carried by the upper part; and there is fast on the rock shaft 239 a toothed segment 246. Arm 242 operates the segment by direct engagement with arm 244 when rocked to the right in Fig. 6 and when it is rocked to the left it operates the segment through a spring 248 surrounding a bolt 250 which passes through openings in arms 242 and 244. The bolt is formed with a fixed head seating against arm 242 and with an adjustable head 252 engaging spring 248.

Segment 246 is in driving engagement with a rack 254 formed on an extension of a sleeve 256 mounted on a reduced portion of the rod or plunger 42 which is operated thereby for opening and closing wipers 30. Sleeve 256 is retained in its place on the reduced end of the rod or plunger 42 by a head 258 and is kept from turning when rod 42 is angularly adjusted with sleeve 44 by guide flanges 260 carried by arms 240 which are in sliding engagement with the upper and lower surfaces of rack 254.

Springs 228 and 248 are quite heavy, as they are not expected to yield during the normal operation of the machine. If, however, for any reason the wipers do not clear the last bottom before the beginning of the overwiping operation, these springs can yield to prevent damage.

By this arrangement it will be observed that operation of rock shaft 218 for advancing and retracting the wipers has no effect on the opening and closing of the wipers, as it merely carries arms 240 and the shaft 239 idly back and forth and therefore swings the top of rock shaft 216 backward and forward without any operative effect upon it and thus without affecting the relation of the wipers to each other. On the other hand, operation of rock shaft 216 is independent of the longitudinal position of sleeve 44, and operates to open and close the wipers without having any effect on their advancing and retracting movements. The different trains of mechanism leading from the operating shaft to the wipers for advancing and for closing the wipers respectively are thus operatively independent of each other; that is, the extent of movement required of either train of mechanism properly to perform its

function is unaffected by the extent of the movement of the other train of mechanism. The wiper-advancing and wiper-closing cams may, therefore, each be designed solely with reference to the particular movement of the wipers to be effected thereby without regard to the movement effected by the other cam. A further advantage of this arrangement is that any bodily yield of the wipers lengthwise of the shoe in the upwiping operation has no effect upon the relation of the wipers to each other. The vertical movements of slide 64 have no effect, either on the closing or the advancing movement of the wipers, due to the use of telescopic shafts and universal joints as parts of the operating connections.

While not limited to such use, a construction such as above described may advantageously be modified as illustrated in Fig. 7, or in an equivalent manner, to vary the amount of advancing and closing movements of the wipers, or so that the amount or rate of closing movement which corresponds to a given advancing movement, or vice versa, may be changed to suit the particular shoe being lasted. So far as I am aware, in all previous machines this ratio has been fixed, and in order to make such a change it has been necessary to remove some of the parts of the machine and replace them by others. In the embodiment of this feature of my invention illustrated in Fig. 7, bell crank levers 190 and 192 are connected to their respective plungers 196 through links 270. Each of these links is pivotally connected at one end to its plunger 196 and at the other end to a block 272 threaded on an adjusting device 274 which is carried by lugs 276 and 278 on bell crank lever 192 (or 190) in such a manner that the adjusting device is restrained against longitudinal movement. Each of the adjusting devices 274 is formed with a knurled head 280, by means of which it may be manipulated. By turning either of the heads 280 the corresponding block 272 is moved up or down to change the effective length of the bell crank lever by which it is carried, in such a manner as to change the extent of movement of plunger 196 corresponding to the throw imparted to the bell crank lever by its cam 146 or 184.

This arrangement is entirely new so far as I am aware, and is useful in changing the machine over from welt to McKay work or vice versa, inasmuch as it is necessary to advance the wipers farther and at the same time to close them farther in overwiping McKay shoes than is necessary or desirable with welt shoes. This novel arrangement is of even greater utility in adjusting for different sizes and styles of welt shoes or McKay shoes as the case may be. It is desirable to wipe in at opposite sides of the toe of a shoe, approximately at the ends of the tip

seam, substantially the same linear distance as the wipers simultaneously move forward over the end of the toe, to provide as nearly as possible for uniform wiping action entirely around the toe. Obviously the amount of angular movement of the wipers necessary to produce this result, for a given amount of advancing movement, depends upon how nearly the sides of the toe approach a relation parallel to the longitudinal median line of the forepart of the shoe, and consequently a greater angular movement of the wipers is necessary, for the best results, on some shoes than on others, for example on pointed toes as compared with round toes. Heretofore it has been necessary, unless the machine was actually changed over by replacing various parts, to design the machine to impart a definite closing movement to the wipers for each increment of advance, in such a manner as to operate most efficiently on a shoe of average size and style. This sort of a compromise has been found to work very well on many kinds of work, but does not permit of securing the extreme accuracy that is possible with the above-described arrangement, which provides for adjusting the machine for each change in the size or style of shoes.

In addition to the above-described adjustments for varying the rate or extent of either the advancing or the closing movement of the wipers, the nuts 208 in cooperation with the sleeve 202 and the spring 200 of the wiper-advancing mechanism may be utilized to adjust the wipers initially lengthwise of the shoe without affecting their relation to each other, and similarly the corresponding parts of the wiper-closing mechanism may be utilized to adjust the wipers toward or from each other without affecting their position lengthwise of the shoe.

It is desirable to render springs 200 ineffective, during the overwiping operation, to prevent on the one hand any yielding of wipers 30 during that operation, and on the other hand to prevent the springs, which at that time have been tensioned by engagement of wipers 30 with the end and side faces of the shoe during the upwiping operation, from projecting the wipers suddenly inward over the shoe bottom. To attain these objects each of the levers 190 and 192 carries a latch 284 so positioned as to engage a rack 286 carried by sleeve 198, the rack being formed to prevent movement of the latch in either direction. Each latch 284 is held out of engagement with its rack during the upwiping operation by a guard member 288 adjustably secured to casing 214, the guard member engaging a pin 290 carried by the latch as shown in Fig. 3. At the conclusion of the upwiping operation, the bell crank levers 190 and 192 have been rocked forward to such positions that the pins 290 ride down

to a thinner portion of the guard members 288, the latches thereby being permitted to engage their racks and lock plungers 196 and sleeves 198 together during the overwiping operation, thus rendering springs 200 ineffective.

In the operation of the machine described above, a pulled-over shoe and its last are placed in the machine, as shown in dotted lines in Fig. 3, the jacking mechanism is operated, and the heel seat is lasted, all as is usual with machines of the bed laster type. Either before or after the lasting of the heel seat, holddown 80 is swung over the forward part of the shoe bottom and clamped thereagainst by manipulation of treadle 98. This operation acts through rack block 112 and link 126 to swing arm 128 in such a manner as to vary the effective length of lever 138 according to the vertical height of the shoe bottom. Wipers 30 are adjusted by manipulation of handles 52, 68, 56 and 66 to align them with respect to the shoe bottom and to position them angularly and lengthwise in proper relation to the toe, and adjusting devices 274 (Fig. 7) are set if this is necessary. Manipulation of handle 52 operates through telescopic shaft 118 to change the position of rack block 112 in such a manner as further to vary the effective length of lever 138 to compensate for any change in the vertical position of the wipers.

Treadle 172 is arranged to control the Horton clutch by moving the 3-arm lever 164 to bring controller 160 or 162 into position to engage one of the stops "a", "b", or "c", or to avoid engaging any of the stops, in such a manner that if the treadle is depressed and immediately released, shaft 148 is turned far enough to operate lever 138 to bring wipers 30 up to a position a predetermined distance below the shoe bottom, as hereinbefore explained, to operate levers 190 and 192 to advance the wipers and close them yieldingly about the end of the shoe, and to operate lever 180 to raise the wipers to the level of the shoe bottom to upwipe the toe under such yielding pressure, whereupon the machine comes to rest, by reason of the action of the controller 162 on the second stop on its clutch disk, to permit arrangement of the upper materials prior to the overwiping operation by manipulation of a hand pincer or otherwise, and to permit inspection of the work to determine if the wipers are properly positioned in relation to the shoe bottom. Cams 146 and 184 are so formed that the remainder of the revolution of shaft 148 serves further to rock levers 190 and 192 first to wipe inwardly over the shoe bottom to an extreme position, then to withdraw almost to the edge of the shoe bottom and then again to wipe inwardly to tacking or wiring position, and finally to return all the parts to their initial positions. During the overwip-

ing operation lever 180 is operated by its cam yieldingly to pull wipers 30 first lightly and then heavily down against the shoe bottom as the wipers move inwardly, to iron the upper materials down upon the shoe bottom, 70 while on each of the retracting movements of the wipers this lever is rocked quickly to release the pressure on the wipers and to lift them so as to prevent them from dragging the upper materials backwardly. To complete the cycle in this manner, the operator will preferably depress the treadle 172 to its lowest position, and with the treadle held or latched in this position the machine will perform the overwiping operations as above 80 explained and the controller 160 will act to stop the machine with the wipers in position to permit the tacking or the wiring of the toe, depending upon whether the shoe is a McKay shoe or a welt shoe. Release of the 85 treadle will then cause the parts to return to their starting positions, where the machine is stopped by the action of the controller 162 on the first abutment of its clutch disk. The operator will then push on the 90 usual knee lever to cause the jacking mechanism and the holddown to release the shoe.

As an alternative to the above-described manner of operation, the operator may at any time, if he desires, render the machine 95 continuously operative by moving the treadle to an intermediate position and holding or latching it in that position. This may be done after the machine has been stopped at the end of the upwiping operation, in 100 which case the wipers will perform the overwiping operations and will then retract and repeat their entire cycle of movements, including both the upwiping and the overwiping operations, as many times as the 105 operator may desire. By properly positioning the treadle, the operator may then cause the machine again to come to a stop at the end of the upwiping operation or in position for the tacking or wiring operation. On the 110 other hand, the machine may, at the start, be rendered operative, upon a full depression of the treadle, to perform the upwiping and then the overwiping operation and to come to a stop in position for tacking or 115 wiring, or by moving the treadle at once to an intermediate position the machine may be caused to go through its entire cycle without a stop and to repeat the cycle one or more times before coming to a stop in any 120 one of its normal stopping positions as may be determined by the operator.

It will be observed that the wipers are moved preliminarily by a shoe-controlled device heightwise of the shoe a distance depending upon the height of the toe and which may be different for different shoes, so that they are closed about the end of each shoe a predetermined distance below the shoe bottom. By this arrangement the upwiping 130

operation on all shoes is carried out in a predetermined manner without special attention from the operator. Wipers 30 are yieldingly closed about the end of the shoe 5 after they have been thus positioned and are held thereagainst during the upwiping operation through the medium of springs 200 so that they may adjust themselves to the contour of the shoe, which is different at 10 different levels, and may yield either lengthwise or laterally of the shoe, and at the conclusion of the upwiping operation they have therefore automatically been adjusted to the contour of the edge of the shoe bottom. At 15 this time the latches 284 operate to render springs 200 ineffective and during the overwiping operation the wipers are controlled in a predetermined manner and substantially positively by cams 146 and 184, while at 20 the same time the wipers are yieldingly depressed in a predetermined manner by the operation of cam 184 on lever 180.

While one embodiment of my invention has been illustrated and described, it is not 25 my intention to limit its scope thereby, inasmuch as certain features of the invention are applicable to machines of different types from that which has been described and to use on various kinds of shoes.

30 Having described the invention, what I claim as new and desire to secure by Letters Patent of the United States is:

1. A lasting machine comprising, in combination, a support for a shoe, toe lasting mechanism, a power-driven shaft, and connections operated by the shaft during a rotation thereof of invariable extent to move said mechanism heightwise of the toe in upwiping engagement with the upper to a variable plane determined by the plane of the bottom of the particular shoe on the support.

2. A lasting machine comprising, in combination, a support for a shoe, lasting mechanism, a power-driven shaft, a cyclic clutch 45 to turn the shaft through a predetermined angle and then stop it, and shoe-controlled connections operated by the shaft during said predetermined turning movement to move said mechanism heightwise of the shoe and bring it to rest in a plane in predetermined relation to the plane of the bottom of the particular shoe on the support.

3. A lasting machine comprising, in combination, a support for a shoe, lasting mechanism, a power-driven shaft and a cam carried thereby, a lever given a definite throw by the cam and connected to said mechanism, and shoe-controlled means for varying the effective length of the lever for moving the lasting mechanism heightwise of the shoe to a position bearing a definite relation to the plane of the shoe bottom.

4. A lasting machine comprising, in combination, a support for a shoe, toe lasting mechanism, a power-driven cam, and con-

nections adjustable under control of the shoe and operated by the cam for moving the lasting mechanism heightwise of the shoe to a position bearing a definite relation to the plane of the shoe bottom.

5. A lasting machine comprising, in combination, a support for a shoe, end-embracing wipers, power-driven mechanism for advancing the wipers and closing them about the end of the shoe and for moving them 75 heightwise of the shoe to a position of rest, and shoe-controlled means for controlling the operation of said mechanism to cause the wipers to come to rest in a plane bearing a predetermined relation to the plane of the 80 shoe bottom.

6. A lasting machine comprising, in combination, a support for a shoe, end-embracing wipers, means for advancing the wipers and for closing them about the end of the 85 shoe, power-driven mechanism including a rotary shaft having an invariable angular movement for effecting relative movement of the wipers and the shoe heightwise of the shoe, and shoe-controlled means for controlling the operation of said mechanism to limit such relative heightwise movement with the wipers in a plane bearing a predetermined relation to the plane of the shoe bottom.

7. A lasting machine comprising, in combination, a support for a shoe, end-embracing wipers, means to close the wipers about the end of the shoe, a power-driven shaft and a lever given a predetermined angular movement thereby to move the wipers 100 heightwise of the shoe, and shoe-controlled connections to determine the effective length of the lever to limit the movement of the wipers differently for different shoes.

8. A machine of the class described having, in combination, a shoe support, toe-embracing wipers, power-driven operating mechanism for moving said wipers heightwise of the toe of the shoe, said operating mechanism comprising parts relatively adjustable to 110 vary the limit of such movement of the wipers, and a device controlled by engagement with the shoe for effecting such relative adjustment in accordance with the location of the plane of the shoe bottom.

9. A machine of the class described, having, in combination, a shoe support, toe-embracing wipers, a cam and power-driven mechanism controlled thereby and including relatively-adjustable parts for moving 120 said wipers heightwise of the toe of the shoe, and mechanism controlled by engagement with different shoes for relatively adjusting said parts to determine different limits of movement of the wipers for the same 125 throw of the cam.

10. A machine of the class described having, in combination, a shoe support, end embracing wipers, shoe-controlled power mechanism for moving the wipers heightwise of 130

the shoe to a plane determined by the shoe and bearing a predetermined relation to the plane of the shoe bottom, and power mechanism to close the wipers about the end of the shoe and hold them in engagement therewith during their movement heightwise of the shoe.

11. A machine of the class described having, in combination, a shoe support, end-embracing wipers, power-driven mechanism for moving the wipers heightwise of the shoe to upwipe the upper, shoe-controlled connections adjustable to limit the movement heightwise of the shoe as determined by the shoe to position the wipers for overwiping at the conclusion of the upwiping movement, and power-driven mechanism for closing the wipers about the end of the shoe and holding them in engagement therewith during the upwiping operation and for thereafter further closing them for overwiping the upper materials.

12. A machine of the class described having, in combination, a support for a shoe, toe-lasting mechanism comprising wipers, power-driven means for moving the wipers differently heightwise of different shoes, a power-driven shaft, and connections from the shaft for advancing and closing the wipers for upwiping the upper materials during their heightwise movement and for then overwiping the upper materials.

13. A machine of the class described having, in combination, a support for a shoe, end-embracing wipers, power-driven means for closing the wipers about an end of the shoe and for holding them in engagement therewith and for further closing them to wipe the upper materials over the shoe bottom, means for moving the wipers heightwise of the shoe while they are held in engagement therewith to upwipe the upper materials and for moving them in the reverse direction after they have begun to close over the shoe bottom to compress the upper materials, and shoe controlled connections to limit the movement of the wipers heightwise of the shoe as determined by the shoe and thereby to insure effective frictional engagement with the upper materials during the first part of their overwiping closing movement.

14. A machine of the class described having, in combination, a support for a shoe, end-embracing wipers, power mechanism for closing the wipers about the end of the shoe and for holding them in engagement therewith, and separate shoe-controlled power mechanism automatically operative in time relation to said first named power mechanism to move the wipers heightwise of the shoe to a variable position determined by the shoe.

15. A machine of the class described having, in combination, a support for a shoe, lasting mechanism, a power-driven member

having a movement of unvarying extent irrespective of the height of the shoe for effecting relative movement of the shoe and said mechanism heightwise of the shoe into predetermined relation to each other, and connections including a shoe-controlled part for varying the extent of the relative movement effected by said power-driven member.

16. A bed lasting machine comprising, in combination, shoe-jacking mechanism, toe-lasting means including wipers for upwiping and overwiping the upper materials of each shoe, power means including a shoe-engaging part and cam-driven connections controlled thereby for moving the wipers differently heightwise of different shoes to position them in a predetermined position with relation to the shoe bottom, and additional cam-driven connections for closing and advancing the wipers timed to cooperate with said first-named connections in upwiping and overwiping the upper materials about the toe of each shoe.

17. A machine of the class described having, in combination, a support for a shoe, means for operating on the bottom of the shoe by movement in a direction substantially parallel to the plane of the shoe bottom, shoe-controlled connections adjustable as determined by the shoe for differently moving said means heightwise of different shoes to a predetermined position relatively to the bottom of each shoe, and power-driven mechanism for operatively moving said means along the bottom of the shoe.

18. A machine of the class described comprising, in combination, a support for a shoe, a slide adjacent thereto and operating mechanism carried thereby, means including a shoe-controlled part for moving the slide differently for different shoes to coordinate the position of the slide and the position of the shoe, and automatic means thereafter operative to move the slide the same distance for all shoes to cause said mechanism to operate uniformly on the different shoes.

19. A machine of the class described having, in combination, a support for a shoe, lasting mechanism, operating means relatively to move the support and said mechanism heightwise of the shoe, and mechanism operating to position the lasting mechanism at the same predetermined distance from the plane of the bottom of each shoe before it operates on the shoe.

20. A machine of the class described having, in combination, a support for a shoe, lasting mechanism, means for moving the lasting mechanism heightwise of the shoe toward the edge of the shoe bottom, and connections including a controlling member engaging the shoe bottom for differently limiting the movement of said mechanism for different shoes to position it a predetermined distance from the edge of the shoe bottom.

mined distance below the bottom of each shoe before it operates on the shoe.

21. A machine of the class described having, in combination, a support for a shoe, lasting mechanism comprising means for laying the upper inwardly over the bottom of the shoe, means relatively to move the support and said mechanism heightwise of the shoe, connections controlled by the shoe
- 10 for variably terminating the relative movement for different shoes to position the lasting mechanism the same predetermined distance from the plane of the bottom of each shoe, and additional connections for relatively moving the support and said mechanism a further predetermined distance in the same direction heightwise of the shoe to position the lasting mechanism for laying the upper materials of each shoe over the
- 20 shoe bottom.

22. A machine of the class described having, in combination, a support for a shoe, end-embracing wipers, means relatively to move the support and the wipers heightwise of the shoe, a shoe-controlled device variably to terminate such relative movement to position the wipers a predetermined distance from the plane of the bottom of each shoe, and additional means for further relatively moving the wipers and the support an automatically determined distance heightwise of each shoe in the same direction as said first relative movement with the wipers held in frictional engagement with the shoe to upwipe the upper materials and for closing the wipers over the bottom of each shoe to overwipe the upper materials.

23. A machine of the class described having, in combination, a support for a shoe, lasting mechanism comprising means for laying the upper inwardly over the bottom of the shoe, means including a shoe-controlled part for moving said mechanism heightwise of the shoe toward the edge of the shoe bottom from an invariable initial position to different positions as determined by different shoes at an invariable distance from the plane of the bottom of each shoe, and means for then relatively moving the lasting mechanism and each shoe a predetermined distance heightwise of the shoe to position the lasting mechanism for laying the upper materials over the shoe bottom.

24. A machine of the class described having, in combination, a support for a shoe, lasting mechanism, shoe-controlled means for differently positioning said mechanism for differently-positioned shoes on the support to bring the mechanism into engagement with each shoe the same distance from the plane of the shoe bottom, and automatic means for relatively moving said mechanism and each shoe to upwipe and overwipe the upper materials.

25. A machine of the class described hav-

ing, in combination, a support for shoes of different sizes and styles constructed and arranged to hold different shoes with their bottoms at different heights, and power-operated shoe-controlled lasting mechanism variably moving relatively to different shoes as determined by the shoes to upwipe their upper materials the same predetermined distance.

26. A machine of the class described having, in combination, a support for shoes of different sizes and styles, end-embracing wipers, power-operated shoe-controlled means for variably moving the wipers heightwise of different shoes to position them a predetermined distance from the plane of the bottom of each shoe, and power-operated means for closing the wipers about each shoe when so positioned and for operating them to upwipe and overwipe the upper materials.

27. A machine of the class described comprising, in combination, a support for a shoe, end-embracing wipers, shoe-controlled mechanism for moving the wipers differently heightwise of different shoes to position them a predetermined distance from the plane of the bottom of each shoe, means yieldingly to close the wipers about an end of the shoe, and means further to move the wipers a predetermined distance heightwise of the shoe to upwipe the upper materials.

28. A machine of the class described comprising, in combination, a support for a shoe, end-embracing wipers, shoe-controlled power-mechanism for moving the wipers differently heightwise of different shoes to position them a predetermined distance from the plane of the shoe bottom, power means for then yieldingly closing the wipers about an end of the shoe, and power means for thereafter further moving the wipers a predetermined distance heightwise of the shoe to upwipe the upper materials.

29. A machine of the class described having, in combination, a shoe support, lasting mechanism, operating mechanism for effecting relative positioning movement of said shoe support and lasting mechanism heightwise of the shoe including parts relatively adjustable to determine the limit of such movement, a device including a member for engaging the bottom of the shoe for effecting relative adjustment of said parts as determined by the shoe, and additional operating means for effecting relative movement of said shoe support and lasting mechanism heightwise of the shoe from the limit of said positioning movement to cause the lasting mechanism to wipe the upper toward the edge of the shoe bottom.

30. A machine of the class described having, in combination, a shoe support, lasting mechanism, operating means for effecting relative movements of said shoe support and

lasting mechanism in the same direction heightwise of the shoe first to position said mechanism and the shoe relatively prior to the operation of said mechanism on the shoe 5 and then to wipe the upper toward the edge of the shoe bottom, and means for determining by engagement with the bottom of the shoe the limit of the relative positioning movement.

10 31. A machine of the class described having, in combination, a shoe support, lasting mechanism, operating means automatically controlled independently of the shoe to impart to said lasting mechanism an upwiping movement of invariable extent irrespective of the shape and position of the shoe, and means controlled by the shoe for determining the position of said lasting mechanism heightwise of the shoe at the beginning 20 of such upwiping movement.

32. A machine of the class described having, in combination, a shoe support, lasting mechanism, operating means automatically controlled independently of the shoe to impart to said lasting mechanism an upwiping movement of invariable extent for all shoes, and shoe-controlled means for setting said lasting mechanism relatively to each shoe at an invariable distance from the plane of the shoe bottom preparatory to such upwiping movement.

33. A machine of the class described having, in combination, a shoe support, lasting mechanism, operating means automatically controlled independently of the shoe to impart to said lasting mechanism an upwiping movement of invariable extent irrespective of the shape and position of the shoe, means for imparting to said lasting mechanism a 35 positioning movement heightwise of the shoe preparatory to said upwiping movement including parts relatively adjustable to determine the limit of said positioning movement, and mechanism for effecting relative 40 adjustment of said parts as determined by engagement with the bottom of the shoe to limit the positioning movement of the lasting mechanism at the same distance from the plane of the bottom of the shoe irrespective of the shape and position of the shoe.

34. A machine of the class described having, in combination, a shoe support, lasting mechanism, means for imparting to said lasting mechanism in the same direction heightwise of the shoe a variably determined positioning movement prior to the operation of said mechanism on the shoe and an invariable upwiping movement, and means controlled by the shoe for determining the 55 extent of said positioning movement.

35. A machine of the class described having, in combination, a shoe support, end-embracing wipers, means for moving said wipers from an initial position in one direction heightwise of the shoe first to position

them relatively to the shoe and then to wipe the upper toward the edge of the shoe bottom, means for closing the wipers about the end of the shoe at an intermediate stage in their movement heightwise of the shoe, and means controlled by the shoe for determining the distance of the wipers from the plane of the shoe bottom when they are closed about the shoe. 70

36. A machine of the class described having, in combination, a shoe support, end-embracing wipers, means for moving said wipers from an initial position in one direction heightwise of the shoe first to position them relatively to the shoe and then to wipe the upper toward the edge of the shoe bottom, mechanism automatically operative at a predetermined time in the movement of the wipers heightwise of the shoe to close them about the end of the shoe to begin the upwiping operation, and mechanism controlled by the shoe for determining automatically the distance of the wipers from the plane of the shoe bottom when they are closed about the shoe. 75 80 85

37. A machine of the class described having, in combination, a shoe support, end-embracing wipers, operating means for moving said wipers heightwise of the shoe, means for closing the wipers about the end of the shoe before they arrive at the end of their path of movement heightwise of the shoe to cause them to wipe the upper toward the edge of the shoe bottom, and means controlled by the shoe for determining for the wipers a closing position at an invariable distance from the plane of the bottom of the shoe irrespective of the shape and position of the shoe. 90 95 100

38. A machine of the class described, having, in combination, a shoe support, end-embracing wipers, means for closing the wipers about the end of the shoe and for effecting in time relation to said closing movement a relative movement of the shoe support and the wipers heightwise of the shoe to cause the wipers to wipe the upper to the edge of the shoe bottom and shoe-controlled means automatically operative prior to the closing of the wipers to set them heightwise 105 110 115 of the shoe at a predetermined distance from the plane of the shoe bottom.

39. A machine of the class described having, in combination, a shoe support, end-embracing wipers, operating means for imparting to said wipers a positioning movement heightwise of the shoe and for then closing them about the end of the shoe and moving them farther in the same direction to wipe the upper toward the edge of the shoe bottom, and means for controlling automatically by engagement with the shoe the distance of the wipers from the plane of the shoe bottom when they are closed about the end of the shoe. 120 125 130

40. A machine of the class described having, in combination, a shoe support, end-embracing wipers, means for moving said wipers heightwise of the shoe first to position them relatively to the shoe prior to their operation on the shoe and then to wipe the upper to the edge of the shoe bottom, and shoe-controlled means for varying the extent of the positioning movement for different shoes without varying the extent of the wiping movement.

41. A machine of the class described having, in combination, a shoe support, end-embracing wipers, operating mechanism comprising members cooperating to move said wipers heightwise of the shoe, separate trains of mechanism for imparting respectively to one of said members a movement of invariable extent and to the other a movement of adjustably variable extent, and shoe-controlled means for varying the extent of movement of said last-named member.

42. A machine of the class described having, in combination, a shoe support, end-embracing wipers, an operating member and connections between said member and the wipers for moving the wipers heightwise of the shoe, additional operating mechanism automatically operative in time relation to said member to effect relative movement of parts of said connections for also moving the wipers heightwise of the shoe, and shoe-controlled means for adjusting said additional mechanism to determine the extent of movement imparted to the wipers by said mechanism.

43. A machine of the class described having, in combination, a support for a shoe, lasting mechanism, and means for relatively moving the support and said mechanism heightwise of the shoe, said means including a movable member and a pair of operating devices therefor, one of said devices being controlled by the shoe to operate said member differently for different shoes to position the lasting mechanism a predetermined distance below the bottom of each shoe, and the other automatically controlled to operate the member the same for all shoes to upwipe the upper materials of the different shoes the same distance.

44. A machine of the class described having, in combination, a support for a shoe, lasting mechanism, and means for relatively moving the support and said mechanism heightwise of the shoe, said means including a rack and pinion and a pair of operating devices therefor comprising an arm carrying the pinion and a second rack to turn the pinion when the arm is stationary and to cause the pinion to roll by remaining stationary when the arm is moved, one of said devices being controlled by the shoe to operate said first-named rack and the pinion differently for different shoes to position the lasting mech-

anism a predetermined distance from the plane of the bottom of each shoe, and the other automatically controlled to operate them the same for all shoes to upwipe the upper materials of the different shoes the same distance.

45. A machine of the class described having, in combination, a support for a shoe, lasting mechanism, a slide and a rack connected thereto for moving the lasting mechanism heightwise of the shoe, a pinion to operate the rack, a second rack engaging the opposite side of the pinion, an arm for bodily moving the pinion when the second rack is stationary to cause the pinion to roll on the rack to move the slide, a second arm for moving the second rack to turn the pinion and move the slide when the first arm is stationary, connections including a shoe-engaging part for moving one of said arms differently for different shoes to place the lasting mechanism in a predetermined position relatively to the shoe bottom, and means to move the other arm the same for all shoes uniformly to upwipe the upper materials of the different shoes.

46. A machine of the class described having, in combination, a support for a shoe, mechanism for operating on the shoe, a slide and a rack connected thereto for moving the mechanism heightwise of the shoe, a pinion to operate the rack, a second rack engaging the opposite side of the pinion, an arm for bodily moving the pinion when the second rack is stationary to cause it to roll on said rack to move the slide, a second arm for moving the second rack to turn the pinion when the first arm is stationary, connections including a shoe-controlled part for moving one of said arms differently for different shoes to place the operating mechanism in a predetermined position relatively to the shoe bottom, and means for moving the other arm the same for all shoes to operate uniformly on the different shoes.

47. A machine of the class described having, in combination, a support for a shoe, end-embracing wipers, shoe-controlled means for bringing the wipers from an invariable initial position to different positions closed yieldingly about the ends of different shoes a predetermined distance from the plane of each shoe bottom, and power means for thereafter moving the wipers to upwipe the upper materials and for then closing them over the bottom of each shoe and moving them yieldingly toward the shoe bottom to compress the upper materials.

48. A machine of the class described having, in combination, a support for a shoe, end-embracing wipers, shoe-controlled means for bringing the wipers from an invariable initial position to different positions closed yieldingly about the ends of different shoes a predetermined distance from the plane of each shoe bottom, and power means oper-

ating in a predetermined cycle to move the wipers to upwipe the upper materials and then to close them over the bottom of each shoe and move them yieldingly toward the shoe bottom to compress the upper materials and finally to bring them to rest in tacking or toe-wiring position.

49. A machine of the class described having, in combination, a support for a shoe, end-embracing wipers, shoe-controlled means for bringing the wipers from an invariable initial position to different positions closed yieldingly about the ends of different shoes a predetermined distance from the plane of each shoe bottom, the wipers being movable in a predetermined cycle to upwipe and over-wipe the upper materials of each shoe, and power means for operating said wipers repeatedly through their cycle during the pleasure of the operator and for then bringing them to rest in tacking or toe-wiring position.

50. A machine of the class described having, in combination, a support for a shoe, end-embracing wipers, shoe-controlled power means for relatively moving the wipers and support differently heightwise of different shoes as determined by the shoes to position the wipers in predetermined relation to the bottom of each shoe, a manually-operable adjusting device for alining the wipers with the shoe bottom, and a connection from said device to vary the action of said shoe-controlled means to compensate for adjustments made by said device.

51. A machine of the class described having, in combination, a support for a shoe, end-embracing wipers, power-operated mechanism for operating the wipers to advance and close them, power means including a part controlled by engagement with the shoe bottom for moving the wipers heightwise of the shoe to a predetermined position with relation to the shoe bottom, a hand-operated device for tilting the wipers to adjust them with respect to the shoe bottom, and a connection from said device for varying the action of said power means to compensate for different adjustments of the wipers.

52. A machine of the class described having, in combination, a support for a shoe, end-embracing wipers, mechanism for moving the wipers heightwise of the shoe, means including a shoe-engaging feeler for differently limiting the movement of the wipers for different shoes to position them a predetermined distance from the plane of the bottom of each shoe, a device for adjusting the wipers relatively to the shoe bottom, a connection from said device for varying the limiting action of said means to compensate for the adjustment of the wipers, and additional mechanism for further moving the wipers a predetermined distance heightwise

of the shoe to upwipe the upper materials 65 of different shoes uniformly.

53. A machine of the class described, having, in combination, a shoe support, end-embracing wipers adjustable to vary the plane of their operative movement and thereby to 70 position them relatively to the shoe, a power-driven operating member, and separate connections between said member and the wipers for advancing and closing the wipers respectively, said connections comprising parts relatively movable in the adjustment 75 of the wipers to maintain operative connection with the wipers in any position in which they are adjusted.

54. A machine of the class described having, in combination, a support for a shoe, end-embracing wipers, a manually-adjustable carrier for the wipers, a drive shaft mounted in fixed bearings, and operating 80 connections between the shaft and the wipers including telescopic rock-shafts and devices operated thereby for advancing and closing the wipers respectively in any position of the carrier without special manual adjustment 85 of the connections.

55. A machine of the class described having, in combination, a support for a shoe, end-embracing wipers, a drive shaft mounted in fixed bearings, a connection 90 from the shaft for moving the wipers heightwise of the shoe, and self-adjusting connections from the shaft comprising parts movable relatively to each other in response to the heightwise movement of the wipers and arranged to advance and close the 95 wipers in a predetermined manner regardless of the extent of such heightwise movement.

56. A machine of the class described having, in combination, a frame formed with fixed bearings, a drive shaft mounted in the bearings, end-embracing wipers, connections from the shaft for moving the wipers heightwise of the shoe, rack mechanism for operating the wipers, and connections from the shaft including rotatable telescopic members for operating said rack mechanism.

57. A machine of the class described having, in combination, a support for a shoe, end-embracing wipers, and separate power-operated means for advancing and for closing the wipers, the power-operated wiper-closing means comprising self-adjusting parts movable relatively to each other in response to the advance of the wipers for maintaining operative connection with the wipers in any position to which they are moved by operation of the advancing means.

58. A machine of the class described having, in combination, a support for a shoe, end-embracing wipers, a movable member for advancing and retracting the wipers, a second movable member connected to the

first member to move therewith and arranged to open and close the wipers, and separate power-driven connections for operating said different members.

5. 59. A machine of the class described having, in combination, a support for a shoe, end-embracing wipers, a sliding plunger for advancing and retracting the wipers, a second and parallel sliding plunger for opening and closing the wipers, mechanism for operating the first plunger, and power-driven means including a part carried by the first plunger for operating the second plunger to open and close the wipers independently of their advancing and retracting movements.

10. 60. A machine of the class described having, in combination, end-embracing wipers, a sliding member for advancing and retracting the wipers, power means for moving said member, a rock-shaft carried by said member to move therewith, connections from the rock-shaft for opening and closing the wipers, and additional power means for rocking the shaft.

15. 61. A machine of the class described having, in combination, a support for a shoe, end-embracing wipers angularly adjustable about a plurality of axes to aline them with the bottom of the shoe, and separate power-driven connections uniformly operable in any position of adjustment of the wipers for advancing and for closing the wipers respectively.

20. 62. A bed lasting machine having, in combination, a support for a last and shoe, end-embracing wipers, a mounting for the wipers constructed and arranged to permit angular adjustment about three different axes, means for advancing and retracting the wipers relatively to the shoe, and additional independently-operable means for opening and closing the wipers, both said means being constructed and arranged to operate in a predetermined manner regardless of the position of adjustment of the wipers.

25. 63. A lasting machine comprising, in combination, a support for a shoe, end-embracing wipers, a mounting therefor permitting angular adjustment of the wipers to aline them with the bottom of the shoe, a slide movable to carry the wipers heightwise of the shoe to upwipe the upper materials, a power-driven telescoping rock-shaft and connections therefrom for advancing the wipers with respect to the shoe, and a second power-driven telescoping rock-shaft and connections for closing the wipers.

30. 64. Wiper mechanism comprising, in combination, a wiper support, end-embracing wipers, wiper-carriers angularly movable on the support for opening and closing the wipers, a rack and pinion for moving the support to advance and retract the wipers, and a second rack and pinion for operating the wiper-carriers.

35. 65. Wiper mechanism comprising, in combination, an adjustable support, a sleeve mounted in the support for angular adjustment about its longitudinal axis, wipers and wiper-carriers mounted on the sleeve, a wiper-closing rod mounted to slide in the sleeve, mechanism for moving the sleeve in the support to advance the wipers, and additional mechanism for independently moving the rod for closing the wipers.

40. 66. Wiper mechanism comprising, in combination, an adjustable support, a sleeve having a wiper-supporting head and mounted in the support for angular adjustment about its longitudinal axis, wipers and wiper-carriers mounted on said head, a wiper-closing rod mounted to slide in the sleeve, mechanism for moving the sleeve in the support to advance the wipers, and additional mechanism carried by the sleeve for independently moving the rod to close the wipers.

45. 67. A machine of the class described having, in combination, a support for a shoe, end-embracing wipers, means relatively to move the wipers and support heightwise of the shoe, means for holding the wipers yieldingly closed about the end of the shoe during such relative heightwise movement to upwipe the upper materials, means to close the wipers over the shoe bottom to overwipe the upper materials, and means to lock the wipers against yielding during their overwiping movement.

50. 68. A machine of the class described having, in combination, a support for a shoe, end-embracing wipers, power mechanism for projecting said wipers over the edge of the shoe bottom to form the margin of the upper materials thereover including yielding means tensioned by contact of the wipers with the shoe before they are moved over the bottom of the shoe, and locking means to prevent the tensioned yielding means from operating the wipers and to prevent yielding of the wipers against the resistance of said yielding means during their projection over the shoe bottom.

55. 69. A machine of the class described having, in combination, a support for a shoe and end-embracing wipers relatively movable heightwise of the shoe to upwipe the upper materials, mechanism for holding the wipers closed about the end of the shoe during the relative upwiping movement and for then closing them over the shoe bottom to overwipe the upper materials, said mechanism including yielding means permitting the wipers to yield to conform to the contour of the shoe during the upwiping movement, and means for preventing further yielding of the wipers during the over-wiping movement.

60. 70. A machine of the class described having, in combination, a support for a shoe, end-embracing wipers, power mechanism for rel-

atively moving the support and wipers heightwise of the shoe, additional power mechanism including yielding means for holding the wipers in yielding engagement with the shoe during the relative heightwise movement to upwipe the upper materials and for then closing them to wipe the upper materials over the shoe bottom, and locking means automatically effective at the end of the upwiping movement to render the yielding means inoperative during the overwiping movement.

71. A machine of the class described having, in combination, a shoe support, end-embracing wipers, operating mechanism for closing said wipers about an end of the shoe and for thereafter advancing and closing them inwardly over the bottom of the shoe, said operating mechanism including spring means arranged to yield in response to the closing pressure of the wipers against the shoe as they are closed about the end of the shoe, and mechanism for preventing further yield of said spring means as the wipers are advanced and closed over the bottom of the shoe.

72. A machine of the class described having, in combination, a shoe support, end-embracing wipers, operating mechanism for closing said wipers about an end of the shoe and for thereafter advancing and closing them inwardly over the bottom of the shoe, said operating mechanism including spring means yieldable in response to the pressure of the wipers against the shoe as they are closed about the end of the shoe, and locking mechanism automatically operative after the wipers have been closed about the end of the shoe to prevent reaction of said spring means and also to prevent further yield of such means as the wipers are advanced and closed over the bottom of the shoe.

73. A machine of the class described having, in combination, a shoe support, end-embracing wipers, operating mechanism for closing said wipers about an end of the shoe and for thereafter closing them inwardly over the bottom of the shoe, said operating mechanism including a spring common to both wipers and yieldable in response to the pressure of the wipers against the shoe as they are closed about the end of the shoe, and locking means for preventing reaction of said spring as the wipers are closed over the bottom of the shoe.

74. A machine of the class described having, in combination, a shoe support, end-embracing wipers, operating mechanism for closing said wipers about an end of the shoe and for thereafter closing them inwardly over the bottom of the shoe, said operating mechanism including a spring common to both wipers and yieldable in response to the pressure of the wipers against the shoe as they are closed about the end of the shoe,

and mechanism automatically operative after the wipers have been closed about the end of the shoe to lock said spring against reaction and also against further yield as the wipers are closed over the bottom of the shoe.

75. A machine of the class described having, in combination, a shoe support, end-embracing wipers, operating mechanism for advancing and closing the wipers about an end of the shoe and for thereafter advancing and closing them inwardly over the bottom of the shoe, said operating mechanism including separate spring means yieldable in response to resistance to the advancing and closing pressures of the wipers respectively, and devices for locking said separate spring means against reaction as the wipers are advanced and closed over the bottom of the shoe.

76. A machine of the class described having, in combination, a shoe support, end-embracing wipers, operating mechanism for advancing and closing the wipers about an end of the shoe and for thereafter advancing and closing them inwardly over the bottom of the shoe, said operating mechanism including separate spring means yieldable in response to resistance to the advancing and closing pressures of the wipers respectively, and devices automatically operative after the wipers have been closed about the end of the shoe to lock said separate spring means both against reaction and against further yield as the wipers are advanced and closed over the bottom of the shoe.

77. A machine of the class described having, in combination, a shoe support, end-embracing wipers, wiper operating means comprising separate trains of mechanism for imparting to the wipers advancing and closing movements respectively, each of said trains of mechanism including a spring yieldable in response to pressure of the wipers against the shoe, and a locking device associated with each spring and operative after the wipers have been advanced and closed about the end of the shoe to prevent further yield of the spring as the wipers are moved inwardly over the bottom of the shoe.

78. A machine of the class described having, in combination, a shoe support, end-embracing wipers, wiper operating means comprising separate trains of mechanism for imparting to the wipers advancing and closing movements respectively, each of said trains of mechanism including a spring yieldable in response to pressure of the wipers against the shoe, and controlling means associated with the different respective springs and automatically operative after the wipers have been advanced and closed about the ends of the shoe to prevent reaction of said springs as the wipers are moved inwardly over the bottom of the shoe.

79. Means for upwiping and overwiping

the upper materials of a shoe comprising, in combination, a shoe support and end-embracing wipers relatively movable heightwise of the shoe, wiper-closing mechanism including 5 yieldingly-connected members, a latch carried by one member and a rack carried by the other, and means to hold the latch in an idle position during the upwiping operation and to bring it into engagement with the rack at 10 the end of the upwiping operation to lock said members together during the overwiping operation.

80. Means for upwiping and overwiping the upper materials of a shoe comprising, 15 in combination, a shoe support and end-embracing wipers relatively movable heightwise of the shoe, mechanism for advancing the wipers bodily lengthwise of the shoe including yieldingly-connected members, a 20 latch carried by one member and a rack carried by the other, and means to hold the latch in an idle position during the upwiping operation and to bring it into engagement with the rack at the end of the upwiping 25 operation to lock said members rigidly together during the overwiping operation.

81. Wiper-operating mechanism comprising, in combination, end-embracing wipers, angularly-movable carriers therefor, mechanism for moving the carriers including 30 yieldingly-connected members, a latch carried by one member and a rack carried by the other, and a guard to hold the latch idle during the first part of the operation of said 35 mechanism to permit the wipers to vary their positions during the upwiping of the upper materials of a shoe and then to allow the latch to engage the rack to lock said members together during the overwiping operation.

40 82. Mechanism of the class described comprising, in combination, end-embracing wipers, means for moving the wipers bodily to advance them and for moving them angularly to close them, and means for varying 45 the relative speeds of the bodily and angular movements to change the amount of one of such movements of the wipers taking place during a given amount of the other of 50 such movements.

83. Means for laying the upper materials of a shoe over the shoe bottom comprising, in combination, end-embracing wipers, mechanism for advancing and for closing the wipers over the bottom of the shoe, and means 55 for adjusting said mechanism to change the amount of advancing movement corresponding to a given closing movement or vice versa.

60 84. A machine of the class described having, in combination, end-embracing wipers, means for advancing said wipers, means for closing them during their advancing movement, and an adjusting device to vary the 65 action of one of said means to change rela-

tively the amounts of advancing and closing movement of the wipers.

85. A machine of the class described having, in combination, end-embracing wipers, means including a pair of lever arms for advancing and closing the wipers respectively, and means for changing the relative effective lengths of the lever arms to vary relatively the amounts of closing and advancing movement of the wipers. 70

86. Lasting mechanism comprising, in combination, end-embracing wipers, power-cyclically operated connections for closing the wipers, and means to adjust said connections to vary the amount of closing movement imparted to the wipers thereby. 80

87. Lasting mechanism comprising, in combination, end-embracing wipers, power-driven cyclically operated connections for advancing the wipers, and means to adjust 85 said connections to vary the amount of advancing movement imparted to the wipers thereby.

88. Lasting mechanism comprising, in combination, end-embracing wipers, power-driven cyclically operated connections for closing and for advancing the wipers respectively, and means for separately adjusting 90 said connections to vary the extent of the closing and to vary the extent of the advancing movement of the wipers. 95

89. Lasting mechanism comprising, in combination, end-embracing wipers, a wiper-operating member, a cam-operated part, and adjustable connections between said member 100 and part for varying the extent of the movement of the wipers without changing the throw of the cam-operated part.

90. Lasting mechanism comprising, in combination, end-embracing wipers, cyclic 105 power means and connections therefrom for operating the wipers to overwipe the upper materials of a shoe, and means to adjust the connections to change the extent of the overwipe effected by said power means. 110

91. Lasting mechanism comprising, in combination, end-embracing wipers, cyclic power means and connections therefrom for closing and for advancing the wipers respectively to overwipe the upper materials of a 115 shoe, and means to adjust said connections separately to change the extent of the closing and of the advancing effected by said power means.

92. Lasting mechanism comprising, in combination, end-embracing wipers, a wiper-operating part having a fixed throw, and adjustable connections from said part for changing the extent of the movement of the wipers effected thereby. 120

93. Lasting mechanism comprising in combination, end-embracing wipers, wiper-operating means having a fixed throw and connections therefrom for advancing and for closing the wipers respectively, and 125 130

means for adjusting said connections separately to change the extent of the closing movement and the extent of the advancing movement effected by said means.

5 94. Lasting mechanism comprising, in combination, end-embracing wipers, a lever arm having a fixed throw, connections therefrom for moving the wipers over the bottom of a shoe, and means for changing the effective length of the lever arm.

10 95. Lasting mechanism comprising, in combination, end-embracing wipers, an operating member having a fixed throw and connections therefrom for relatively moving a shoe and the wipers lengthwise of the shoe to overwipe the upper materials of the shoe, and means for adjusting said connections to change the extent of the relative movement effected by said member.

15 96. Lasting mechanism comprising, in combination, end-embracing wipers, operating means having a fixed throw and connections therefrom for relatively moving a shoe and the wipers lengthwise of the shoe and for closing the wipers to overwipe the upper materials of the shoe, and means for adjusting said connections separately to change the extent of the relative movement and the extent of the closing movement effected by said means.

20 97. Means for overwiping the upper materials of shoes comprising, in combination, end-embracing wipers, mechanism for advancing the wipers bodily and for turning them about the end of a shoe to close them, and an adjusting device to change the amount of closing movement for a given advancing movement to preserve a desired relation between the amount the wipers are projected over the end of the toe and over the sides at the ends of the tip seam in operating on shoes of different sizes in which the tip seams are different distances from the ends of the toes.

25 98. A machine of the class described having, in combination, lasting means, drive mechanism therefor, a treadle, and connections therefrom to stop said mechanism with the lasting means in wiring or tacking position when the treadle is depressed, and to start the mechanism and again stop it with said means in initial position when the treadle is thereafter released.

30 99. A machine of the class described comprising, in combination, upper-forming mechanism, power-driven connections for operating said mechanism, stopping and starting means to control said connections and to bring them to rest in any one of a plurality of automatically determined positions other than starting position, and a manually-controlled member movable in different ways selectively to operate said means.

35 100. A lasting machine comprising, in

combination, end-embracing wipers, mechanism for relatively moving a shoe and said wipers heightwise of the shoe and for advancing and closing the wipers, power driving means for said mechanism, and a treadle 70 and connections therefrom for controlling the driving means, the connections being so constructed and arranged that the treadle may be operated alternatively to bring the wipers to rest (1) in a position closed about 75 the end of the shoe in predetermined relation to the shoe bottom, or (2) in wiring or tacking position.

101. A lasting machine comprising, in combination, end-embracing wipers cyclic 80 mechanism for relatively moving a shoe and said wipers heightwise of the shoe and for advancing and closing the wipers, power driving means for said mechanism, a treadle and connections therefrom for controlling the driving means, the connections being so constructed and arranged that the treadle may be operated alternatively (1) to bring the wipers to rest in a position closed about 85 the end of the shoe in predetermined relation to the shoe bottom, or (2) to bring them to rest in wiring or tacking position, or (3) to cause them to repeat their cycle during the pleasure of the operator.

95 102. A machine of the class described having, in combination, a shoe support and end lasting mechanism relatively movable in an automatically determined cycle to last a shoe, and controlling mechanism including a manually operated controlling member 100 movable to different positions to stop the relative movement of said shoe support and lasting mechanism at different points in the cycle.

103. A machine of the class described having, in combination, a shoe support and end lasting mechanism relatively movable in an automatically determined cycle to wipe the upper heightwise of the shoe and inwardly over the bottom of the shoe, and controlling mechanism including a manually operated controlling member movable selectively to different positions to stop the relative movement of said shoe support and lasting mechanism either at the end of the 115 upwiping operation or at the end of the overwiping operation.

110 104. A machine of the class described having, in combination, a shoe support and end lasting mechanism relatively movable in an 120 automatically determined cycle to last a shoe, and controlling mechanism including a manually operated controlling member movable in one direction to stop the relative movement of said shoe support and lasting mechanism at one point in the cycle and movable in a different direction to stop such relative movement at another point in the cycle.

125 105. A machine of the class described hav-

ing, in combination, a shoe support and end lasting mechanism relatively movable in an automatically determined cycle, and controlling mechanism including a manually operated controlling member movable to different positions to stop the relative movement of said shoe support and lasting mechanism at different points in the cycle and movable to another position to cause automatic repetition of the cycle.

106. A machine of the class described having, in combination, a shoe support, end lasting mechanism, power-driven means for operating said lasting mechanism, and controlling means comprising a manually operated controlling member movable in one direction to start said power-driven means and thereafter to stop it automatically with the lasting mechanism in predetermined relation to the shoe, said member being movable in another direction again to start said means in operation.

107. A machine of the class described having, in combination, a shoe support, toe embracing wipers mounted for movement heightwise of the shoe and inwardly over the bottom of the shoe, and operating mechanism for imparting to said wipers in an automatically determined cycle a single movement heightwise of the shoe to wipe the upper to the edge of the shoe bottom and a plurality of inward movements over the bottom of the shoe.

108. A machine of the class described having, in combination, shoe-positioning means, end-embracing wipers mounted for preliminary tipping movement to adjust them relatively to the shoe, an operating member, and different universal connections between said member and the wipers for imparting respectively to the wipers advancing movement and closing movement in any position to which they are tipped.

109. A machine of the class described having, in combination, shoe-positioning means, end-embracing wipers, and means for operating said wipers comprising an operating member and different trains of mechanism leading therefrom for imparting respectively to the wipers advancing movement and closing movement each of predetermined extent unaffected by the extent of the other.

110. A machine of the class described having, in combination, shoe-positioning means, end-embracing wipers, and means for operating said wipers comprising an operating member and different trains of mechanism leading therefrom for imparting respectively to the wipers advancing movement and closing movement each of predetermined extent unaffected by the extent of the other, each of said trains of mechanism being independently adjustable to vary the extent of the movement of the wipers effected thereby.

111. A machine of the class described having, in combination, shoe-positioning means, end-embracing wipers, an operating member, a train of mechanism leading from said member to the wipers for advancing the wipers bodily lengthwise of the shoe, said train of mechanism being adjustable to vary the extent of the advancing movement of the wipers, and another train of mechanism leading from said member for imparting to the wipers closing movement of predetermined extent unaffected by the extent of their advancing movement.

112. A machine of the class described having, in combination, shoe-positioning means, end-embracing wipers, and means for operating said wipers comprising an operating member and different trains of mechanism leading therefrom for imparting respectively to the wipers advancing movement and closing movement, each of said trains of mechanism being adjustable preliminarily to vary the initial position of the wipers determined thereby without affecting the position determined by the other train of mechanism.

113. A machine of the class described having, in combination, shoe-positioning means, end-embracing wipers, and means for operating said wipers comprising an operating member and different trains of mechanism leading therefrom for imparting respectively to the wipers advancing movement and closing movement, the wiper-advancing mechanism being adjustable preliminarily to advance or retract the wipers bodily lengthwise of the shoe without affecting their relation to each other.

114. A machine of the class described having, in combination, shoe-positioning means, end-embracing wipers, an operating member, a train of mechanism leading from said member to the wipers for advancing the wipers bodily lengthwise of the shoe, and a second train of mechanism leading from said member to the wipers for closing the wipers, said second train of mechanism being operatively independent of the first train of mechanism.

115. A machine of the class described having, in combination, shoe-positioning means, end-embracing wipers, an operating member, a train of mechanism leading from said member to the wipers for advancing the wipers bodily lengthwise of the shoe, and a second train of mechanism leading from said member to the wipers for closing the wipers, said second train of mechanism including a power-transmitting element carried by the first train of mechanism and operatively independent of the movement of said first train of mechanism.

116. A machine of the class described having, in combination, shoe-positioning means, end-embracing wipers, an operating mem-

ber, connections between said member and the wipers for advancing the wipers bodily lengthwise of the shoe, said connections including a power-transmitting element movable forwardly with the wipers, and connections between said operating member and the wipers for closing the wipers including a power-transmitting element arranged to be moved forwardly with said first element 10 and operatively independent of the forward movement of the latter.

117. A machine of the class described having, in combination, shoe-positioning means, end-embracing wipers, an operating member, connections between said member and the wipers for advancing the wipers bodily lengthwise of the shoe, and mechanism operated by said member to close the wipers including universal connections arranged to 20 be carried forwardly with the wipers and operatively independent of the forward movement of the wipers.

118. A machine of the class described having, in combination, shoe-positioning means, 25 end-embracing wipers, an operating member, connections between said member and the wipers for advancing the wipers bodily lengthwise of the shoe, said connections including a power-transmitting element movable forwardly with the wipers, a rock shaft mounted for bodily forward movement with said element and connected to the wipers to close them, and connections between said operating member and rock shaft operatively

independent of the forward movement of 35 the wipers.

119. A machine of the class described having, in combination, shoe-positioning means and end-embracing wipers relatively movable heightwise of the toe of a shoe to wipe the upper, a wiper-operating member, connections between said member and the wipers for advancing the wipers bodily lengthwise of the shoe constructed to permit yielding bodily movement of the wipers 45 lengthwise of the shoe in response to resistance of the shoe in the upwiping operation, and connections between said operating member and the wipers for closing the wipers laterally of the shoe, said last-named 50 connections being constructed to maintain the wipers in a relation to each other unaffected by their bodily yield lengthwise of the shoe.

120. A machine of the class described having, in combination, a shoe support, toe-embracing wipers, and power-driven operating mechanism for effecting in an automatically determined cycle a single relative movement of said shoe support and wipers 60 to wipe the upper heightwise of the toe and a plurality of relative movements to wipe the upper repeatedly inward over the shoe bottom.

In testimony whereof I have signed my 65 name to this specification.

ARTHUR F. PYM.

CERTIFICATE OF CORRECTION.

Patent No. 1,662,253.

Granted March 13, 1928, to

ARTHUR F. PYM.

It is hereby certified that error appears in the printed specification of the above numbered patent requiring correction as follows: Page 6, line 64, for the misspelled word "ides" read "sides"; page 8, line 4, after the word "yieldingly" strike out the comma, and line 109, claim 8, after the word "operating" insert the word "mechanism"; page 16, line 77, claim 86, after the word "power" insert the word "driven"; page 17, line 80, claim 101, after the word "wipers" insert a comma; and that the said Letters Patent should be read with these corrections therein that the same may conform to the record of the case in the Patent Office.

Signed and sealed this 16th day of April, A. D. 1929.

M. J. Moore,
Acting Commissioner of Patents.
